UNITED STATES PATENT OFFICE.

STEVE TAKÁCS, OF NEWARK, OHIO, ASSIGNOR OF ONE-THIRD TO ANDREW PERETZKY,
OF NEWARK, OHIO.

WAGON.

1,180,206.

Specification of Letters Patent. Patented Apr. 18, 1916.

Application filed March 8, 1915. Serial No. 12,859.

To all whom it may concern:

Be it known that I, STEVE TAKÁCS, a subject of the Emperor of Austria-Hungary, residing at Newark, in the county of Licking and State of Ohio, have invented certain new and useful Improvements in Wagons, of which the following is a specification.

My invention relates to wagons of the type designed for use in conveying heavy 10 and massive articles from place to place.

The main object of my invention resides in the provision of a wagon having a sectional bed, sectional in that that portion between the front and rear wheels may be 15 raised and lowered between the ground line and the normal bed level.

A further object of my invention resides in providing a crank operated structure and a jack operated structure for causing movement of the movable portion of the wagon bed. I desirably provide this structure for the reason that some structures of small bulk may be particularly heavy and at times this weight is such that it is impossible for 25 one man to move the wagon bed by the crank operated structure. He then can resort to the jack operated structure, which gives the aided leverage necessary.

The preferred embodiment of my invention is shown in the accompanying sheets of drawings, in which similar characters of reference designate corresponding parts, and in which;

Figure 1 is a side elevation of my wagon 35 showing the bed in lowered position in broken lines. Fig. 2 is an end elevation of the structure shown in Fig. 1, looking toward the left, Fig. 3 is a view looking down on the operating mechanism carried by the 40 rear portion of the vehicle, Fig. 4 is a section taken on line 4—4 of Fig. 3, and looking in the direction of the arrows, Fig. 5 is a section taken on line 5—5 of Fig. 3 and looking in the direction of the arrows, and, Fig. 45 6 is a view showing the jack operating handle.

In the drawings, the running gear is shown as comprising front and rear wheels 1 mounted upon a suitable type of front 50 and rear supporting structure designated in its entirety by the reference numeral 2. Each of the front and rear supporting structures is also provided with a bed portion 3, these bed portions being so constructed as 55 to lie in the same plane with the major or

movable bed portion shown at 4. Posts 5 and 6 extend upwardly one each side of each of the front and rear supporting structures 2 and are bridged at their top by a rigid tie piece shown at 7. It is to be understood that the general wagon structure may be of any type desired, it being essential only that tie pieces of some nature such as are shown at 7 are used, in order that the front and rear supporting structures 2 may be held in rigid connection. In order that the movable and stationary portions of the vehicle bed may be held in locked engagement so that the tie structure may be supplemented, I have provided each side with a 60 pair of locking members such as shown at 8, each of these locking members being pivoted to the stationary portions of the vehicle by means of eye bolt shown at 9, while their opposite ends are provided with eyes 10 in order that they may register with outwardly projecting studs 11. These locking members are held in their locked 65 positions by means of clasps shown at 12, the latter being pivoted at one end, as shown 70 at 13, to the body of the movable portion of the bed 4. It will be understood that by bringing the locking members 8 into engagement with the studs 11, the wagon bed 75 80 85 90 95 100 105 110 4 may be held in its locked position and in this manner supplement the tie structure 7. In order to positively hold the locking members in position, the clasp members 12 are provided, these latter operating in the manner shown particularly in Fig. 1.

In order to control the movement of the movable portion of the wagon bed 4, I have provided an operating shaft 14, this shaft being suitably journaled upon the stationary portion 2 forming the support of the rear wagon wheels. Each end of this shaft is provided with a double drum structure as shown at 15, upon which cables 16 and 17 are adapted to be wound, the cable 16 passing up along the side of the rear posts 5, over a double sheave structure shown at 18 and then down to a point of attachment with the rear end of the movable bed portion 4. The other cables 17 pass over similar sheaves 18 then forward along the tie piece 7, over sheaves shown at 19 and then down to their points of attachment to the forward end of the movable bed portion 4. Both cables are also guided in their vertical movements by means of supplemental sheaves shown at 20.

In order to operate the shaft 14, I have provided it with a ratchet wheel shown at 21, this ratchet wheel being rigidly mounted upon this shaft and being prevented from moving in a reverse direction by means of the pivoted pawl shown at 22. In order to operate the ratchet, I have provided a jack pawl 23, this pawl being pivoted at 24 to a hollow rectangular casing 25. This casing 10 is pivoted at 26 to depending bearing members shown at 27 and it is into this casing that the operating handle designated 28 and shown in Fig. 6 is adapted to fit. The pivoted end of the pawl 23 is also provided 15 with a counterweight portion 29 in order to always hold the forward end of the pawl in engagement with its ratchet. By inserting the operating handle 28 into the tubular casing 25, as shown in broken lines in Fig. 4 20 and then moving the free end toward the ground, the pawl 23 is given an upward movement and because of its engagement with the ratchet wheel 21, this ratchet wheel and its supporting shaft 14 are given a partial turn. The pawl 22 automatically falls 25 in position by gravity to prevent reverse movement of the ratchet, which gives the operator an opportunity of again moving the operating handle 28 up to get a second 30 grip on the ratchet. This jack operating means is necessarily somewhat slow in accomplishing the elevation of the movable portion of the bed and where the load being supported is such that an unusually large 35 amount of power is not required, the crank operating means shown in Fig. 5 may be resorted to. This crank operating means comprises a worm wheel 30 carried upon a sleeve 31, this latter being loosely mounted upon 40 the shaft 14. Arranged to coöperate with the worm wheel 30 is a worm 32 formed on a transverse shaft 33 suitably journaled in bearings shown at 34 and being provided with an operating crank 35 at its forward end. In order to provide some type 45 of clutch arrangement to give a rigid connection between the loosely mounted gear 30 and the shaft 14, I have pivoted a dog 36 to the ratchet wheel 21, as shown, this dog being pressed toward teeth 37 on one face of 50 the gear 30 by means of the leaf spring shown at 38. It will, therefore, appear that the gear 30 will rotate free of the shaft 14 in one direction and with this shaft in its opposite direction because of the engagement 55 between the rigidly mounted ratchet 21 caused by the pivoted dog 36. This dog 36 is so arranged that rotation of the crank 35 to rotate the worm 32 in a manner to cause elevation of the movable portion of the bed 4 will establish a rigid connection between the 60 worm wheel 30 and the shaft 14. In the opposite direction, the weight on the movable portion 4 will be sufficient to at all times 65 keep the dog 36 in engagement with the

teeth on the worm wheel and this worm wheel is prevented rotating freely because of the driving connection it has with the worm 32. The loose mounting of the gear 30 on its shaft 14 is necessary for the reason that 70 when the jack structure is operated, the ratchet wheel 21 and shaft 14 must rotate to elevate the wagon bed, while rotation of the worm wheel 30 is impossible unless the worm 32 is also operated.

In order to render the jack operating structure inoperative to permit the use of the crank operating structure, I have provided a shelf member 39 rigidly attached to a pivot bolt 40 carrying a crank 41 at its 80 forward end. The shelf under the control of this crank 41 is so arranged that when moved to the left as shown in Fig. 2, it will assume the position shown in dotted outline in Fig. 4 to engage the counter-weight portion 29 of the pawl of the jack operating structure, thus throwing its engaging end out of engagement with the ratchet wheel 21 as is also shown in broken outline in Fig. 4. A similar structure in the nature of a bar 90 42 mounted at one end upon a pivot bolt 43, this latter also carrying an operating crank 44, is provided to throw the pawl 22 out of its operative position, this inoperative position being also shown in dotted outline in 95 Fig. 4, which inoperative position is caused by movement of the operating crank 44 to the left as shown in Fig. 2.

From the foregoing description, it will be apparent that I have provided a wagon of 100 comparatively simple structure wherein the major portion of the bed may be moved between the ground line and the normal bed elevation. The structure for carrying out this operation is such that under comparatively light loads the movement may be effected rapidly, while under heavy loads the jack operating structure may be resorted to, which necessarily gives a somewhat 105 slower elevation. Movement of the pawls 22 and 23 to the positions shown in dotted outline in Fig. 4 permits the use of a crank operated structure wherein the worm and worm wheel 32 and 30 serve as a lock against accidental lowering movement of the bed 110 portion 4. Operation of the crank 35 from the top down toward the left, permits the shaft 14 to rotate because of the applied weight on the bed. Movement of the crank 35 in an opposite direction, establishes a 115 connection between the worm 30 and the ratchet wheel 21 through the medium of the pivoted pawl 36 and, therefore, the shaft 14 will also be rotated notwithstanding the loose mounting of the gear 30. In this manner, the bed may be elevated. In case it is desired to use the jack operating structure, the operating cranks 41 and 44 are moved to the positions shown in Fig. 2, which permits the pawls 22 and 23 to assume the positions 120 125 130

shown in Fig. 4. Insertion of the operating handle 28 into the tubular casing 25 and oscillating it as is common will cause this ratchet wheel 21 and consequently the shaft 14 to rotate to also elevate the wagon bed 4. Because of the loose mounting of the worm wheel 30 on the shaft 14, this rotation of the shaft and ratchet will be free of the worm wheel, but if, for any reason, the pawl 2 should become inoperative, the pawl 36 will serve as a check since it is always in engagement with the teeth on the face of the worm 30, and this worm is locked against movement because of its engagement with the worm 32 on the shaft 33.

15 What I claim, is:

1. A wagon comprising a running gear, a sectional bed, said bed being divided to permit movement up and down of that portion 20 between the front and rear wheels, crank operated means whereby said movable bed portion may be given such movement, and jack operated means for elevating said bed.

2. A wagon comprising a running gear, a 25 sectional bed, said bed being divided to permit movement up and down of that portion between the front and rear wheels, an operating shaft, operating means connecting said shaft and the movable part of said bed,

a worm wheel loosely mounted on said shaft, 30 a worm arranged to mesh with said worm wheel, a ratchet keyed to said shaft, a jack operated pawl arranged to coöperate with said ratchet, and a ratchet and pawl connection between said first named ratchet and 35 said worm wheel.

3. A wagon comprising a running gear, a sectional bed, said bed being divided to permit up and down movement of the entire width portion between the front and rear 40 wheels, an operating shaft, operating means connecting said shaft and the movable part of said bed, a worm wheel loosely mounted upon said shaft, a worm arranged to mesh with said worm wheel, a ratchet wheel keyed 45 to said shaft, a set of teeth on the side face of said worm wheel, a pawl pivotally mounted on the side face of said ratchet and arranged to coöperate with said teeth, and a jack operated pawl arranged to coöperate 50 with said ratchet.

In testimony whereof I affix my signature in presence of two witnesses.

STEVE TAKÁCS.
